DUMPING BAILER

George L. Matson, Kilgore, Tex., assignor to The Dow Chemical Company, Midland, Mich., a corporation of Michigan

Application April 7, 1945, Serial No. 587,073

3 Claims. (Cl. 166—19)

The invention relates to apparatus adapted for lowering pulverulent or granular materials, such as gravel, into deep wells or the like.

One of the objects of the invention is to provide a dumping bailer capable of handling granular materials having a high angle of repose. Another object is to provide a device of the aforesaid character which is of simple construction and in which the charge is securely and positively locked in the bailer so that premature unloading is avoided. Another object is to provide a dumping bailer having the aforesaid advantages and additionally provides for positive assistances in evacuation of the charge on dumping the bailer. Still other objects and advantages of the invention will appear as the description proceeds, the accompanying drawing and following description setting forth in detail a mode of practicing the invention.

In the drawing:

Fig. 1 is a side elevation of the apparatus largely in section completely assembled in position for loading and lowering into the well.

Fig. 2 is a cross section on the line 2—2 of Fig. 1.

Fig. 3 is a cross section on the line 3—3 of Fig. 1.

Fig. 4 is an enlarged fragmentary view of a portion of Fig. 1.

Fig. 5 is a similar view to Fig. 1 showing the position of the parts when unloading or dumping the bailer.

In the several figures, like numerals refer to like parts.

Referring more particularly to the drawing, the bailer comprises a container 1 of generally cylindrical form having a diameter slightly less than the well it is to enter and of suitable length to hold the charge of pulverulent material to be dumped. The container is open at the top 2 and bottom 3. Attached to the top 2 of the container is a pair of upper arms 4 supporting the upper guide 5 having a bore 6 in axial alignment with the container. The bottom 3 of the container is similarly provided with a lower pair of arms 7 for supporting the lower guide 8 having a bore 9 in axial alignment with the container.

Mounted in the bore 6 of the upper guide 5 in sliding relationship therewith is the upper end of the agitator 10 on which is mounted the upper stop 11 and lower stop 12 for limiting the longitudinal movement of the agitator in the guide 5. At least the lower portion 13 of the agitator 10 is tubular. Near the lower end of the agitator are mounted the centering arms 14 which serve to center the agitator in the container, and agitate

At the lower end of the container, closure plates 15 of semi-circular form are provided. These are hinged inside the container by pivots 16 running through the apertured brackets 17 mounted on the bottom of the plates and the supporting apertured brackets 18, respectively, mounted on the inside of the container at diametrically opposite points. In the closed position, as shown in Fig. 1, the closure plates abut against the lower end 19 of the agitator which acts as a stop to limit their upward swing when the agitator is pulled up so that its lower stop 12 abuts the upper guide 5.

In the bore 9 of the lower guide member 8, there is mounted the anchor bar 20 in sliding relationship, upper and lower anchor stops 21 and 22, respectively, limiting its longitudinal movement, being provided on the anchor above and below the lower guide member 8. Between the upper anchor stop 21 and the guide 8, a compression coil spring 23 is provided for urging the anchor 21 upward.

Attached to the upper anchor stop means 21 is the closure support 24 which telescopes with the agitator 10. For holding the closure plates 15 in the closed position (as shown in Fig. 1) a shear pin 25 is inserted in an opening 26 in the closure support 24.

The anchor bar 20 is provided at its lower end 30 with a foot 27 for engaging the bottom of the well. For suspending the apparatus, a rope or cable 28 may be secured to the upper end of the stop 11 by means of a rope socket 29.

In operation, the apparatus is suspended in the vertical position by the suspending means as shown in Fig. 1, whereby the weight of the container and associated parts is borne on stop means 12 on which, therefore, then rests the upper guide means 5. The agitator 10 is thereby held in its upper position, the length of the agitator bar below the lower stop 12 being such that when in the upper position the lower end 19 limits the upward swing of the closure members 15 to the horizontal or closed position, as shown, as these members are urged upwardly by the shear pin 25 in support 24 in turn urged upwardly by the action of compression spring 23. The charge of pulverulent material is introduced into the container through the top 2. The charged container is lowered into the well and dumped by allowing the foot member 27 to strike the bottom of the well. The descent of the container continues due to its weight while 27 remains on the bottom of the well hole, thereby forcing the end 19 of the agitator bar 10 to press downward on the closure

members 15 forcing them against the shear pin 25 which ruptures. As a consequence, the closure members swing open as shown in Fig. 5 allowing the contents to be dumped.

To facilitate unloading or dumping the bailer cylinder, an up and down motion may be imparted to the suspending cable 28 and, hence, to the agitator centering arms 14. This motion agitates the contents of the cylinder, thereby overcoming any tendency for the contents to bridge or fail to flow out of the cylinder once the closure members are opened.

After the container is unloaded as described, the apparatus is withdrawn from the well and the closure members 15 swing into the horizontal position as shown, the device is then ready for reloading and a shear pin inserted in 26 to hold the plates in closed position.

I claim:

1. A dumping bailer for lowering a pulverulent material into a well comprising a container for holding a quantity of pulverulent material to be dumped; a pair of closure plates, each hinged at diametrically opposite points inside and near the bottom of the container and together adapted to form a closure for the container; an upper guide member supported by the upper end of the container; an agitator within the cylinder having a tubular lower end, the upper end extending through the said upper guide means in sliding relationship; stop means on the agitator above and below the upper guide member and adapted to limit its longitudinal travel with respect to said upper guide means; lower guide means supported by the lower end of the container; an anchor bar mounted in the said lower guide means in sliding relationship therewith; stop means on the anchor bar above and below the said lower guide means adapted to limit its longitudinal travel with respect to the said lower guide means; spring means mounted on the said anchor bar above the said lower guide means adapted to urge the said anchor bar upwardly; a closure supporting bar having its lower end secured to the anchor bar and its upper end extending into the lower end of the agitator bar; and a shear pin means in the closure supporting bar adapted to engage the bottom of the said closure plates and hold them against the bottom of the agitator bar in closed position, said shear pin rupturing and allowing the plates to swing open when downward travel of the bailer in the well is arrested by the anchor bar striking the bottom of the well.

2. A dumping bailer for lowering a pulverulent material into a well comprising a container for holding a quantity of pulverulent material to be dumped; a pair of closure plates each hinged inside and near the bottom of the container and together adapted to form a closure for the container; an upper pair of arms each secured to diametrically opposite points on the top of the container; an upper guide member supported by the upper pair of arms having an opening therethrough in axial alignment with the container; an agitator bar within the cylinder having a tubular lower end, the upper end extending through the opening in said upper guide in sliding relationship; stop means on the agitator above and below the upper guide member adapted to limit

its longitudinal travel with respect to the upper guide member; a lower pair of arms each secured to diametrically opposite points on the bottom of the container; a lower guide member supported by the lower pair of arms having an opening therethrough in axial alignment with the container; an anchor bar extending through the opening in the said lower guide member in sliding relationship therewith; stop means on the upper end of the anchor bar above and below the lower guide member to limit its longitudinal travel with respect to the lower guide member; spring means on the anchor bar above the said lower guide means adapted to urge the said anchor bar upwardly; a closure supporting bar having its lower end secured to the anchor bar and its upper end extending into the lower end of the agitator bar; and a shear pin means in the closure supporting bar adapted to engage the bottom of the said closure plates and hold them against the bottom of the agitator bar in closed position, said shear pin rupturing and allowing the plates to swing open when downward travel of the bailer in the well is arrested by the anchor bar striking the bottom of the well.

3. A dumping bailer for lowering a pulverulent material into a well comprising a container for holding a quantity of pulverulent material to be dumped; a pair of closure plates each hinged inside and near the bottom of the container and together adapted to form a closure for the container; an upper pair of arms each secured to diametrically opposite points on the top of the container; an upper guide member supported by the upper pair of arms having an opening therethrough in axial alignment with the container; an agitator bar within the cylinder having a tubular lower end, the upper end extending through the said upper guide member in sliding relationship; centering arms secured to the agitator bar; stop means on the agitator bar above and below the upper guide member adapted to limit its longitudinal travel with respect to the upper guide member; a lower pair of arms each secured to diametrically opposite points on the bottom of the container; a lower guide member supported by the lower pair of arms having an opening therethrough in axial alignment with the container; an anchor bar extending through the opening in the said lower guide member in sliding relationship therewith; stop means on the anchor bar above and below the lower guide member to limit its longitudinal travel with respect to the lower guide member; spring means mounted on the said anchor bar above the said lower guide means adapted to urge the said anchor bar upwardly; a closure supporting bar having its lower end secured to the anchor bar and its upper end extending into the lower end of the agitator bar; and a shear pin means in the closure supporting bar adapted to engage the bottom of the said closure plates and hold them against the bottom of the agitator bar in closed position, said shear pin rupturing and allowing the plates to swing open when downward travel of the bailer in the well is arrested by the anchor bar striking the bottom of the well.

GEORGE L. MATSON.
